UNITED STATES PATENT OFFICE.

AMMON TAYLOR, OF NEWTOWN, CONNECTICUT.

COMB.

SPECIFICATION forming part of Letters Patent No. 250,298, dated November 29, 1881.

Application filed August 26, 1881. (No model.)

To all whom it may concern:

Be it known that I, AMMON TAYLOR, of New-
town, in the county of Fairfield and State of
Connecticut, have invented a new and useful
5 Improvement in Combs; and I do hereby de-
clare that the following is a full and accurate
description of the same.

This invention relates to that class of combs
which are provided with double or re-enforced
10 backs; and it consists in the hereinafter-de-
scribed mode of attaching said backs to the
combs.

Combs of horn, ivory, &c., are necessarily
made about the same thickness at the back as
15 through the teeth, because of the difficulty of
procuring the material of desirable thickness or
the costly character of the material. The first
reason applies to horn, and the last applies to
ivory. The transverse grain of horn, ivory,
20 &c., also makes the comb frail and liable to
break across the back. To guard against this
liability backs of metal, wood, &c., have been
applied, inclosing the back edge of the comb,
and thereby strengthening it to the desired de-
25 gree. When metal backs have been employed
longitudinal grooves have been cut along the
sides of the comb, near to the back edge, and
the edges of the metal were placed in the same,
being held firmly therein by the elasticity of
30 the metal. This makes a serviceable back; but
it is objectionable because the acids formed by
decomposition of the oily matters acquired
from the hair attack the metal and corrode it.
Aside from metal, wood has been most com-
35 monly employed, and has been secured by riv-
ets. As a material wood is probably the most
desirable; but as the wooden back is necessar-
ily made with grain running lengthwise of the
comb, and is not subject to expansion and con-
40 traction in that direction, whereas the grain
of the comb is transverse to its length, and
therefore is liable to expansion and contrac-
tion, it is evident the attachment of the wooden
back by rivets must be frail. Therefore the
45 desideratum is a non-corrodible back, secured
to the comb in a way which will permit the
comb to expand and contract lengthwise with-
out loosening the attachment of the back, and
the same forms the gist of my invention.

50 That others may fully understand the inven-

tion, I will more particularly describe it, hav-
ing reference to the accompanying drawings,
wherein—

Figure 1 is a perspective view of my inven-
tion, a portion being broken away to show the
interior structure. Fig. 2 is an end elevation
of the same. Fig. 3 shows the old way of at-
taching wooden and other backs. Fig. 4 shows
the common way of attaching metallic backs.

A is the comb, made in the ordinary way, ex-
cept that at each end the back is cut a little
longer than the teeth, as shown at b. One or
more grooves, d, are cut in the side or sides of
the back longitudinally, and the back F, pref-
erably of wood, but possibly of some other
65 proper material, is fitted over the back by hav-
ing cut in said back a deep longitudinal groove
of proper width to receive and fit the back of
the comb, as shown. When the back is applied
to the comb the grooves are filled with glue
70 or other proper cement, which will harden and
adhere to the wood, but not to the comb, and
which will not be softened by the oily matters
from the hair. After application the wood is
clamped to the comb-back until the glue or ce-
75 ment has become hard, and the wooden back
is then anchored to the comb by hard and
strong ribs e e, which are not only not likely
to split off, as ribs left cutting the wood would
do, but they serve more effectually to strength-
80 en the wood itself than equal portions of the
wood itself would do. These ribs of glue do
not adhere to the comb, and therefore the comb
is free to expand or contract.

To prevent the back F from slipping end-
wise on the comb a simple rivet, r, may be put
through both back and comb, and to prevent
the wood from checking and splitting at the
ends, and to impart to the attachment addi-
85 tional strength without preventing expansion
or contraction of the comb, as well as to orna-
ment the ends, ferrules or caps h are applied to
the ends, as shown, so as to inclose the project-
ing parts b.

Having described my invention, what I claim
95 as new is—

1. A comb, A, provided with one or more
longitudinal grooves along the sides of the back,
and back F, fitted over the back of the comb A,
combined with fillings e e, of glue or other prop-
100

er cement, which adheres to the wood, but not to the comb, substantially as and for the purpose set forth.

2. The method of securing re-enforce backs to combs, which consists in grooving the comb-back and forming in said grooves anchor-ribs on the covering reinforce back, from glue or other proper cement which will adhere to said re-enforce, but not to the comb, substantially as set forth.

3. The comb A, provided with the end projections, b, and the back F, extending over said projections, combined with the ferrules h, where-

by the ends are protected and bound, as set forth.

4. A comb, A, provided with the end projections, b, and the longitudinal grooves d, combined with a back, F, anchor-ribs e e, of glue or other proper cement adhesive to the back, but not to the comb, and the binding-ferrules h at the ends, as set forth.

AMMON TAYLOR.
